UNITED STATES PATENT OFFICE.

THOMAS I. DUFFY, OF CHICAGO, ILLINOIS, ASSIGNOR, BY MESNE ASSIGNMENTS, TO THE WEATHERPROOF CONSTRUCTION COMPANY, A CORPORATION OF NEW YORK.

SUPPORTING AND GLAZING CONSTRUCTION FOR SKYLIGHTS AND LIKE STRUCTURES.

1,156,351.

Specification of Letters Patent. Patented Oct. 12, 1915.

Application filed November 30, 1908. Serial No. 465,320.

To all whom it may concern:

Be it known that I, THOMAS I. DUFFY, a citizen of the United States, and a resident of Chicago, in the county of Cook and State 5 of Illinois, have invented certain new and useful Improvements in Supporting and Glazing Construction for Skylights and Like Structures; and I do hereby declare that the following is a full, clear, and exact 10 description thereof, reference being had to the accompanying drawings, and to the letters of reference marked thereon, which form a part of this specification.

This invention relates to improvements in 15 skylight and other generally similar constructions composed in part of sheets or panes of glass and in part of metal frame work which supports the glass and arranged to provide weather-proof joints between the 20 adjacent margins of the glass. The load supporting and glazing members are commercially known as skylight or weather-proof glazing bars, and it is these bars to which my invention more specifically re- 25 lates.

Among the objects of the invention is to provide an exceedingly simple, durable and efficient device of this character, arranged for carrying a maximum load with a minimum weight of material.

A further object of the invention is to provide an improved means for providing a weather-proof joint between the upper surface of the glass and the glazing bars carried by the load supporting member.

A still further object of the invention is to provide an improved sealing strip which may be employed in this and other constructions for forming the joint between the glass 40 and the glazing bars.

As shown in the drawings:—Figure 1 is a fragmentary, perspective view of a skylight construction showing one form of the supporting and glazing structure, and two 45 adjacent panes of glass supported thereon. Fig. 2 is a fragmentary plan view of a skylight construction embodying my invention. Fig. 3 is a fragmentary, longitudinal section, illustrating means for supporting over- 50 lapping panes or sheets of glass of an inclined skylight structure. Fig. 4 is a detail section on line 4—4 of Fig. 3. Fig. 5 is a section illustrating a sealing strip em-

ployed in the construction. Fig. 6 is a similar view of the sealing strip showing its 55 form when in service. Fig. 7 is a fragmentary, perspective view of the folded strip, portions of which form the glass carrying flanges or ledges. Fig. 8 is a fragmentary, perspective view of one form of glazing 60 bar. Fig. 9 is a transverse section of a slightly modified form of the "glazing bar". Fig. 10 is a fragmentary section illustrating another manner of cushioning the glazing 65 bars.

While in the drawings I have illustrated my invention as particularly applied in skylight construction, it is to be understood that it is not limited thereto, but that my improved structure may be used for a great 70 variety of other work, such as vertical window work and the like. The glass supporting or glazing bar of my construction may be used either vertically in window work as a mullion, or may be run horizontally if de- 75 sired, and may be placed in the latter manner in skylights if found necessary.

When used in skylight construction the main load carrying member of my improved supporting and glazing structure consists 80 of a flat bar 10 arranged edgewise and which is adapted to be supported at its ends at the ridge and eaves of the skylight structure on suitable supports (not shown). 11, 11 designate the panes of glass that are supported 85 at their margins on and carried by the load carrying member. The said panes of glass are supported on the load carrying member 10 through the medium of folded sheet metal strips, designated as a whole by 12, 12, 90 arranged one on each side of the load carrying members. Under some circumstances the load-carrying member may be provided 95 with other means than the folded metal strips for the purpose of engaging and supporting the panes of glass; for example, the load-carrying member may take the form of a T-bar, the flanges of which engage and support the glass. Each of said folded strips comprise a web portion 13, 13 which is riveted or otherwise secured to the load carrying member, an upper glass carrying flange or ledge 14 extending laterally from the load carrying member, and a lower, laterally extending trough-shaped flange 15 100 arranged parallel with the load carrying 105

member and constituting a trough or gutter through which water of condensation collecting below the glass is drained off. Cushioning strips 16 are placed between the glass carrying ledges or flanges 14 and the edges of the glass and afford cushions between the glass and the relatively rigid ledges, and also serve as supporting surfaces which conform to any irregularity in the glass and 5 present a uniform surface for engagement of all parts of the glass with the supporting surface. The said cushioning strips may be made of felt, rubber, cork, leather or lead. When made of relatively substantial material 10 they may be provided with ribbed supporting surfaces, as shown to adapt them to uneven surfaces of the glass.

The means shown in Figs. 1 to 8, inclusive, for providing a water-proof joint at 20 the upper side of the glass in order to prevent water and snow from finding their way around the inner or adjacent margins of the glass are made as follows:

The load carrying member 10 extends 25 above the level of the panes of glass between adjacent panes and on each side of said load carrying member is arranged a glazing bar 17 which is disposed in a plane generally oblique to the plane of the vertical load 30 carrying member. The upper marginal part 18 of each glazing bar 17 is arranged vertically and is engaged with a downwardly facing shoulder 21 formed on the lower side of a rib or bead 19 on the upper 35 edge of said load carrying member, there being a longitudinal shoulder on each side of said member. Said shoulders are preferably slightly under-cut, as shown in Figs. 1 and 4. The intermediate portion 20 is disposed at an oblique angle to the plane of the load carrying member. The lower side of each glazing bar is preferably curved, as shown at 25, and its lower edge is engaged with and is pressed upon a sealing strip 22 40 which lies on the upper face of the glass.

The said glazing bars 17 are held in place with their edges engaged with the shoulders on the load carrying member and the sealing strips 22 by means of screws 23 arranged 45 obliquely with respect to the plane of the load carrying member and extending through oblong openings in the glazing bars and at right angles to the web or intermediate portion 20 thereof. Said bolts have 50 screw-threaded engagement at their inner ends, beneath said glazing bars, with brackets 24 carried by the load carrying member. The said brackets 24 are each made of a metal bar which extends through an opening 55 in and is fixed to the load carrying member and the ends of the bar are bent downwardly at oblique angles to the plane of the load carrying member. The oblique ends of the brackets are provided with screw-threaded 60 apertures to receive the screws 23. The

heads of said screws are slotted to receive a screw-driver or like implement to insert the same in place. Cushioning or resilient washers 26 are interposed between the heads of the screws and the outer faces of the oblique 70 web portions of the glazing bars. The pressure exerted by the screws 23 has the effect of closely pressing the upper edges of the glazing bars against the shoulders of the load carrying member, and, by reason of the slight undercut arrangement of said shoulders, the possibility of water passing around the upper edges of said bar is eliminated.

The sealing strips 22 herein shown, and constituting one feature of my invention, are of peculiar construction to provide a good weather-proof joint between the glazing bars and the glass. Said strips are made of any suitable material having a substantial body, as lead, cork, rubber, leather and the like. 80 The cross-sectional shape of the strip is such that when pressure is transmitted thereto through the medium of the glazing bars, the strips change their cross-section to embrace the lower edges of the glazing bars and conform closely to the upper sides of the glass faces. To this end said sealing strips are provided at their upper edges with grooves 85 28 (Fig. 5) which fit the lower edges of the glazing bars. The lower sides of said strips are grooved or arched, giving each strip two laterally separated, parallel lips 29 for contact with the glass.

By reason of the construction described, and of the soft material of which the strips are made, when pressure is applied to said strips, (as when the screws 23 are tightened) the strips are mashed or distorted so as to close the grooved upper sides thereof closely about the lower edges of the glazing bars 17, 100 while the parallel, separated lips 29 at the lower sides of the strips are spread apart and mash down upon the glass in the manner indicated in Fig. 6. In this manner, the extent of bearing between the sealing strips 105 and glazing bars and the lower sides of said strips and the glass is increased and the strips are caused to follow any irregularities in the upper surface of the glass. The effectiveness of the sealed joints between the strips and glass on one hand and the glazing bars on the other hand are increased. This latter feature of construction is especially important when the skylight or other structure is built up of what is known as wire 110 glass, inasmuch as the surface of the glass is rough and uneven. This form of sealing strip may be employed in connection with glazing bars of other constructions where it is desired to provide a weather-proof joint 115 between the edge of a pane or sheet of glass and its supporting member or structure.

In Figs. 3 and 7 I have shown an arrangement whereby the panes or sheets of glass 11 of inclined skylight or like structure are sup-

ported to overlap at their edges, the lower edge of one pane of glass overlapping the upper edge of the next lower pane. In connection with such an arrangement, I have shown a special form of the folded strip 12 which thus supports the glass panes in overlapped relation. In this form of the folded strip the upper margin of the web 13 thereof is bent laterally to form glass carrying ledges 14¹, 14², etc., arranged in planes parallel to the planes of the glass sheets or panes which they support and oblique to the pitch plane of the skylight or other structure. The ledges 14¹, 14², etc., at each side of each load carrying member 10 are formed integral parts of a single folded strip which is coextensive in length with the supporting member. The said ledges 14¹, 14², etc. are separated a short distance at their adjoining ends by cutting away a portion of the metal before the ledges are folded. Each pane of glass extends at its lower margin a distance beyond its carrying flange or ledge in overlapping relation to the upper margin of the next lower sheet or pane, which latter margin extends to the upper end of its carrying ledge. Between the overlapping margins of the sheets or panes of glass are arranged sealing strips 22 which support the lower marginal parts of the panes and afford a weather-proof joint between overlapping panes. Said sealing strips may be made of any suitable relatively soft material and are provided on their upper and lower surfaces with parallel longitudinal ribs which serve to closely adapt the strips to the uneven surface of the glass. In a complete skylight structure such strip extends from one "glazing bar" to the next adjacent one.

An advantage of the folded strips described is that I am able to make such strips continuous with the supporting or load carrying member 10, while providing means for supporting the glass panes in overlapping relation. The structure, as a whole, is thus greatly strengthened; it being apparent that the webs of the continuous strips, bolted or riveted as they are to the load carrying members, reinforce said load carrying member and permit the parts to be made of smaller dimensions while providing a relatively great load carrying capacity.

The glazing bars 17 are made of a length equal to that of the marginal parts of the glass panes which they cover. Each glazing bar terminates short of the upper end of its associated pane, as herein shown, and extends beyond the lower end of said pane for overlapping engagement with the glazing bar associated with the next lower pane, as shown in Fig. 3. In order to adapt the glazing bars 17 to the differential planes of the glass panes and the general pitch plane of the skylight structure, the upper vertical

marginal portions 18 of the glazing bars are sheared or cut at an angle to bring the shoulder engaging edges thereof parallel to the shoulders beneath the enlargements or ribs 19 of the load carrying members and at an oblique angle with respect to the lower edges of said glazing bars and the planes of the glass panes. The upper ends of said vertical marginal portions of the glazing bars are, therefore, widest and they taper toward their lower ends, as clearly shown in Figs. 3 and 8. The adjacent ends of the vertical portions 18 of the glazing bars fit in overlapping relation to each other beneath the shoulders of the ribs 19 of the load carrying members, said shoulders being made wide for this purpose.

In case the glass panes be arranged in abutting relation and do not overlap, as herein shown, the glazing bars may be made of uniform width throughout their length. In such construction the pitch of the panes will correspond to the pitch plane of the skylight or like structure.

In Fig. 9 I have shown a construction wherein the glazing bars at the opposite sides of the load carrying members 10, instead of being made of two parts, consist of a single cap portion, designated as a whole by 45. The said glazing cap consists of oblique web portions 46, 46 having their lower edges 47 curved to engage with the sealing strips 22, and are connected at their central portions by integral, downwardly opening channels 48 which fit over the plane upper edges of the load carrying members 10. In this construction, the glazing caps are attached to the load carrying members by short rods 49 which extend through and have a tight or driving fit at their central portions in openings in the load carrying members. Said rods are bent upwardly and outwardly in diverging relation from the load carrying members and extend through openings in the webs 46 of the caps 45. The outer ends of said rods are screw-threaded to receive nuts 50, between which and the webs of the caps are interposed cushioning springs 51. The cushioning springs 51, shown in Fig. 9, are volute springs, the inner turns of which are extended at the outer ends of the springs in the form of a cone for engagement with the nuts 50 or washers 52 between said nuts and springs. The said springs are compressible in the lines of their axes. An advantage of this form of spring is that in case it should break or lose its resiliency by the action of heat or otherwise the nut or washer will be brought against a solid abutment when the spring is fully compressed. In practice, the range of movement of the spring as a cushioning member, when the nut is turned downwardly thereon, is slight so that in case of loss of resiliency or breaking of the spring but

little movement of the nut would be required to bring said nut up against a solid abutment. This feature of construction will be found valuable in cases of impairment of 5 the spring due to heat or other causes, as the solid connection or abutment afforded between the same and its co-operating nut will prevent separation of the parts supported by the rods or bolts on which the nuts 10 are threaded.

A generally similar result may be secured by the use of the spiral spring 55, shown in Fig. 10, when used in connection with a sleeve 56 surrounding the bolt 57 inside the 15 spring and which terminates just short of the bolt head 58 when the spring is placed under compression.

An advantage of the double type of glazing bar arranged one on each side of and 20 separately supported on the load carrying member lies in the fact that in case of breakage of a single pane of glass it is necessary, in order to replace said pane, to remove only two glazing bars, one at each side of the 25 broken pane.

It is to be understood that variations in the structure of details may be made within the scope of the claims hereto appended and I do not limit myself to such details except 30 as they are hereinafter made the subject of specific claims.

In the foregoing description I have referred to the member 10 of my skylight or window bar or "glazing bar", as such a skylight or window bar is often designated in 35 practice as the "load-carrying member". In skylight construction the load upon this member is primarily the weight of the glass and of snow, etc., while where the bar is used 40 in vertical window work the load is primarily due to wind pressure. I do not use the term "load-carrying member" in a restricted sense, but mean the same to express broadly the idea of the main strength-giving 45 or stiffening member of the bar. In like manner the term "glass-carrying ledge" is not to be considered in a limited manner as necessarily actually supporting the weight 50 of the glass, but is that part of the window or skylight bar against which the glass abuts and is held by the glazing strip.

I claim as my invention:—

1. In a skylight and like structure, a load carrying member comprising a flat bar arranged on edge, a glass carrying ledge extending laterally from said member, a pane of glass supporting on the ledge, a yieldingly supported glazing bar engaging at one margin said load carrying member, a sealing strip engaged between the other margin of said glazing bar and the pane of glass, said sealing strip being made of relatively soft imperssible material which is formed with a groove on its upper side to receive the

margin of the glazing bar and on its lower 65 side with laterally separated, longitudinal glass engaging lips, said lips being adapted to be separated under the pressure of the glazing strip and to conform to the inequalities of the face of the glass. 70

2. In a skylight and like structure, a load-carrying member provided with a laterally extending glass-carrying ledge, a pane of glass supported on said ledge and a cushioning strip made of comparatively soft imperssible material between said ledge and pane having a plurality of longitudinally arranged laterally separated glass engaging ribs of V shaped section. 75

3. In a skylight and like structure, where- 80 in the upper courses of the glass panes are arranged in overlapping relation to the lower courses, a load carrying member, glass carrying ledges extending laterally from the load carrying member and arranged in successively lower planes, and glazing bars at the sides of the load carrying member and arranged to press on the surface of the glass panes, the load carrying member having a longitudinal shoulder against which the 90 adjacent margins of the glazing bars bear, the margins of the glazing bars which bear against said shoulders being inclined obliquely to the planes of the glass panes upon which said glazing bars press. 95

4. In a skylight and like structure, where- 100 in the upper courses of the glass panes are arranged in overlapping relation to the lower courses, a load carrying member comprising a flat bar arranged on edge, glass carrying ledges extending laterally from the load carrying member, a glazing bar arranged obliquely to the load carrying member, the load carrying member being provided with a longitudinal shoulder against 105 which the glazing bars bear, means for providing a weather-proof joint between the other margins of the glazing bars and glass, and means for resiliently supporting the glazing bars on the glass and load carrying 110 member, the margins of the glazing bars engaging said shoulder being arranged obliquely to the planes of the glass panes upon which said glazing bars press. 115

5. In a skylight and like structure, a glazing bar having a marginal portion adapted for engagement with a supporting or load carrying structure, and an oblique portion adapted at its other margin for engagement with the glass of the skylight or like structure, the edge of the marginal portion of the glazing bar supported by said member being cut obliquely to the line which separates the latter marginal portion and oblique portion of the bar. 120

6. The combination with a glazing bar, of a soft imperssible sealing strip arranged for engagement with the glass sheet, said seal-

- ing strip being provided on one side with a groove to receive one edge of the glazing bar and at its other side with laterally separated, longitudinal lips adapted for engagement with the glass.
7. The combination with a load carrying member having a ledge for supporting a pane of glass, of a glazing bar supported at the margins by said member, and a relatively soft impessible sealing strip grooved at one side to receive one margin of said bar and provided at its opposite side with laterally separated, longitudinal glass engaging lips.
- 15 8. A relatively soft impessible sealing strip for the purpose set forth provided on one side with a groove to receive a glazing bar and at its other side with two laterally separated longitudinal glass engaging lips.
- 20 9. In a skylight and like structure where in the upper courses of the glass panes are arranged in overlapping relation to the lower courses, a load-carrying member comprising a flat bar arranged on edge and a glass-supporting member attached to the side of said bar, said member being formed from a blank of sheet metal having portions of its upper edge bent laterally away from said bar in steps to form a plurality of integral glass supporting ledges, the lower edge of said member being bent out to form a continuous gutter.
- 25 10. In a skylight and like structure, a glass-supporting member formed from a blank of sheet metal, said member being adapted for attachment to a load-carrying member and being provided at its upper margin with a plurality of laterally extending integral ledges arranged in steps, said ledges being formed by cutting transversely into the upper edge of the blank at intervals, the strips of metal between cuts being folded at an angle to the body of the blank.
- 30 11. In a skylight and like structure, a glass supporting member formed from a blank of sheet metal, said member being adapted for attachment to a load carrying member and being provided at its upper margin with a plurality of laterally extending integral ledges, arranged in successively lower planes, said ledges being formed by cutting the blank transversely at predetermined intervals to form cuts of different lengths, and the strips of metal between the cuts being sheared and folded to form ledges longitudinally parallel to the required pitch.
- 35 12. In a skylight and like structure, a main or load-carrying member comprising glass-supporting portions and a web projecting between the edges of adjacent panes of glass supported on said portions, obliquely disposed sheet metal glazing members engaging said panes, and fastening devices for said glazing members, said devices includ-
- ing the portions passing transversely through openings in said web and portions extending obliquely to the plane of said web and engaging said glazing members.
- 40 13. In a skylight and like structure, a main or load-carrying member comprising glass-supporting portions and a web projecting between the edges of adjacent panes of glass supported on said portions, glazing members engaging said panes, a piece projecting transversely through said web, and bolts or screws carried by said piece and engaging said glazing members.
- 45 14. In a skylight and like structure, a main or load-carrying member comprising glass-supporting portions and a web projecting between the edges of adjacent panes of glass supported on said portions, glazing members engaging said panes and having outer surfaces oblique to the planes of said panes, a piece projecting transversely through said web and having its opposite ends bent into planes substantially parallel with the outer surfaces of said glazing members, and bolts or screws carried by said piece and extending through the glazing members substantially at right angles to the outer faces thereof.
- 50 15. In a skylight and like structure, a main or load-carrying member comprising a glass-supporting portion and a web extending beyond the edge of a pane of glass supported on said portion, substantially at right angles to the plane of said pane, a glazing member engaging said pane, and a fastening device for said glazing member carried by the projecting portion of said web outside of the outer surface of said pane and projecting obliquely to the plane thereof.
- 55 16. In a skylight and like structure, a main or load-carrying member comprising a glass supporting portion and a web extending beyond the edge of a pane of glass supported on said portion, substantially at right angles to the plane of said pane, a glazing member engaging said pane, and a fastening device for said glazing member carried by the projecting portion of said web outside of the outer surface of said pane and projecting obliquely to the plane thereof, said fastening device including means for exerting a yielding pressure upon said glazing member.
- 60 17. In a skylight and like structure, a main or load-carrying member comprising a glass-supporting portion and a web extending beyond the edge of a pane of glass supported on said portion, substantially at right angles to the plane of said pane, a glazing member engaging said pane, and a fastening device for said glazing member comprising a portion passing transversely through an opening in said web outside of the outer surface of said pane and a portion

diverging from said surface and from the plane of said web and engaging said glazing member.

18. A sealing strip for use in skylight and like structures formed of comparatively soft imperssible material and having a plurality of longitudinally arranged laterally separated glass-engaging ribs of V-shaped section upon at least one side thereof.

19. A sealing strip for use in skylight and like structures having a plurality of longitudinally arranged, laterally separated, low, glass engaging ribs, formed of soft imperssible material; the side walls of the ribs converging to form ribs having sharp edges, capable of being easily upset to conform to irregularities in the surface of the glass.

20. In a skylight and like structure, in combination, two overlapping panes of

glass, and means for sealing the joint between said panes comprising a sealing strip of soft imperssible metal inserted between the overlapping portions of said panes, said strip having a plurality of ribs formed upon each of its glass-engaging surfaces, the side walls of said ribs converging to form ribs having sharp edges, capable of being easily upset to conform to irregularities in the surface of the glass.

In testimony that I claim the foregoing as my invention I affix my signature in the presence of two witnesses, this 6th day of November A. D. 1908.

THOMAS L. DUFFY.
